(57) **CLAIM**

The ornamental design for a display case and display tray combination, as shown and described.

DESCRIPTION

FIG. 1 is a top-front perspective view of a display case and display tray combination.

FIG. 2 is a top-front perspective view of a display case and display tray combination with the hinged door open in an alternative position.

FIG. 3 is a top-front perspective view of a display tray.

FIG. 4 is an exploded top-front perspective view thereof.

FIG. 5 is a front-side elevational view thereof, the rear-side being a mirror image.

FIG. 6 is a left-side elevational view thereof, the right-side being a mirror image.

FIG. 7 is a front-side elevational view of a display case and display tray combination.

FIG. 8 is a rear-side elevational view thereof.

FIG. 9 is a right-side elevational view thereof.

FIG. 10 is a left-side elevational view thereof.

FIG. 11 is a top-side plan view thereof; and,

FIG. 12 is a bottom-side plan view thereof.

Any broken line illustration of environmental structure in the drawing is not part of the design sought to be patented.
